UNITED STATES PATENT OFFICE

GEORGE F. FISHER, OF PROVIDENCE, RHODE ISLAND, ASSIGNOR TO THE REVER RUBBER COMPANY, A CORPORATION OF RHODE ISLAND

RIM-FINISHING MACHINE

1,381,177.

Specification of Letters Patent. Patented June 14, 1921.

Application filed July 9, 1920. Serial No. 395,094.

To all whom it may concern:

Be it known that I, GEORGE F. FISHER, a citizen of the United States, residing at Providence, county of Providence, and State 5 of Rhode Island, have invented certain new and useful Improvements in Rim-Finishing Machines, of which the following is a full, clear, and exact description.

This invention relates to the manufacture 10 of tires, and particularly to apparatus for facilitating the treatment of annular members in connection therewith.

In the manufacture of solid tires, by way 15 of example, it is customary to prepare the rims for the reception of a hard rubber base by removal of rust from the channel and coating the same with cement. The rust is removed by sand blasting and subsequently blowing off the particles of foreign matter 20 that may remain. Thus cleaned, the rim is brushed with cement in a room at a suitable temperature to expedite drying. The blowing and coating operations heretofore have been performed by mounting the rims on a 25 spider or chuck of some sort. Such devices have been found objectionable because they require too much time and labor.

The present invention aims to provide an apparatus that requires a minimum of labor 30 in the manipulation of the rims incident to their treatment, and that is of such a simple nature that the services of unskilled operators may be utilized.

With the embodiment of the invention 35 illustrated in the drawings in mind, and without intention to necessarily restrict its scope, the invention may be said to consist of rotating parallel members or shafts by which any number of rims may be sustained 40 upright and treated conveniently while turned thereby.

These are the objects of my invention, and other objects will appear from the accompanying drawings, in which—

45 Figure 1 is a view of the apparatus in perspective, and

Fig. 2 is a typical rim section.

As shown in the drawings the apparatus comprises spaced parallel members or shafts 50 1 and 2 which are suitably supported at spaced intervals in standards 3 and intermediately steadied by blocks 4. The shafts 1 and 2 are preferably but not necessarily

located in a horizontal plane at a convenient elevation above the floor. Both of the shafts 55 are intended to be driven, but for some purposes friction surfaces might be provided on a driven shaft and the other allowed to remain stationary or run free. Any suitable means may be employed to drive the shafts 60 such as the belt pulleys 5, shown at one end thereof.

It is desirable but not essential to maintain the temperature of the air in the vicinity of the shafts at a suitably elevated degree to expedite drying of the cement. For this purpose coils or pipes 7 are located in the rear of and parallel with the shafts or otherwise arranged, and steam or other suitable heating medium may be supplied there- 70 to to maintain the desired temperature.

With the above described apparatus, rims 6 that have been blasted free of rust or other foreign matter are placed upon the shafts and by their own weight frictionally driven 75 about their axes. So mounted, an operator may pass along in front of any number of these rims and blow them clear of minute particles of rust or other matter. Then the rims may be brushed with cement. In 80 both these operations, no manipulation of the rims is necessary beyond placing them upright upon the shafts. It is to be observed that the apparatus is capable of handling any size rim and that regardless of its size the 85 peripheral speed of the channels or grooves thereof remains the same.

While it is preferred to arrange the shafts in a horizontal plane, it is to be distinctly understood that the invention is not limited 90 to such form for the shafts might be located in a plane inclined to the horizontal and the rims held upright and rotated. And the apparatus is not limited in its usefulness to coating rims with cement as it may be 95 employed advantageously adjacent and parallel calendering machines for winding warm sheets of vulcanized composition on the rims and without bothersome manipulation of the easily distorted stock. The invention is 100 therefore not limited to the uses mentioned or details of construction illustrated and described except as indicated in the accompanying claims to which reference is made for an understanding of the scope of the invention. 105

Having thus described my invention, what

I claim and desire to protect by Letters Patent is:—

1. Apparatus of the class described comprising, spaced parallel driven shafts, bearings supporting said shafts at the ends and intermediately, said shafts being adapted to support and turn annular rims between their bearings, and having their entire length substantially free and unobstructed upwardly for the reception of a plurality of the rims.

2. Apparatus of the class described for independently supporting and rotating a plurality of annular tire rims comprising, parallel driven shafts upwardly free and unobstructed for substantially their entire length and of a diameter and spacing between centers such that rims may be supported and rotated in an upright position

thereon and such that unobstructed ready access to the rims is afforded operatives for manual operations thereon.

3. Apparatus of the class described for independently supporting and rotating a plurality of annular tire rims comprising, parallel driven shafts supported adjacent and in proximity to the floor and upwardly free and unobstructed for substantially their entire lengths, said shafts being of a diameter and spacing between centers such that rims may be supported and rotated in an upright position thereon and such that unobstructed access to the rims is afforded operatives for performing manual operations thereon while standing on the floor.

Signed at Providence, Rhode Island, this 28 day of June, 1920.

GEORGE F. FISHER.
